UNITED STATES PATENT OFFICE.

JOHN HAYWARD PARSONS, OF FERNDALE, MICHIGAN, ASSIGNOR, BY MESNE ASSIGNMENTS, TO GUSTAVE A. CARLSON, OF DETROIT, MICHIGAN.

WINDOW REGULATOR.

Application filed July 18, 1923. Serial No. 652,229.

This invention relates to means for regulating the height of windows of automobiles and the like, and has for its primary object the provision of simple and positive means for raising and lowering the windows and maintaining them at any desired position.

A further object is the arrangement of gear-driven lifting and lowering mechanism equally adaptable to right and left side windows, and operable with or without means for counterbalancing the weight of the windows.

A further object is the mounting of locking mechanism adjacent the operating handle which will automatically engage to hold the window in any adjusted position the instant the handle is released and be instantly disengaged when the handle is again turned in either direction.

Other objects and advantages will be apparent from the following description wherein reference is made to the accompanying drawings illustrating preferred embodiments of my invention, and wherein similar reference numerals designate similar parts throughout the several views.

In the drawings:

Fig. 1, is a perspective view of an automobile equipped with my improved window regulating mechanism.

Fig. 2 is a sectional view through the handle and operating gears.

Fig. 3 is an enlarged detail view showing the position assumed by the window and lifting means when the window is at the top-most position.

Fig. 4 is a side elevation of the regulating mechanism with parts broken away.

Fig. 5 is a detail sectional view taken substantially on the line 5—5 of Fig. 4.

Fig. 6 is a detail elevation of the locking mechanism with the parts in locking position.

Fig. 7 is a similar view with the parts in disengaged position.

Fig. 8 is a detail view showing the regulating mechanism associated with means for counterbalancing the weight of the window.

Fig. 9 is a detail sectional view taken substantially on the line 9—9 of Fig. 8, and

Fig. 10 is a detail view of a section of the chain employed.

Referring now to the drawings, the numeral 5 designates an automobile having a plurality of windows 6 adapted to be ver-

tically moved in the usual manner, being lowered into pockets in the frame when it is desired to admit air to the body of the car. The lower edge of the window 6 fit into a channeled carrier-bar 7 having a slotted portion 8 for the reception of the stud 9 of the trailer block 10 secured at one extremity of a lifting and lowering chain 11 (see Fig. 3). The chain 11 is guided in a pair of spaced vertical slots 12 in a channeled guide plate 13 secured in the pockets of the car frame below the window openings, as by screws 14. When the window is opened to its fullest extent the trailer block 10 rests at the lower extremity of the left hand slot 12 in Fig. 4 and the chain 11 passes upwardly therefrom, around the sprocket wheel 15 and into the right hand slot 12, and the length of the chain is proportioned so that when the window is completely closed the opposite extremity of the chain contacts with the lower end wall of the right hand slot 12 to provide a stop for the window.

An additional stop is provided however by the conformation of the trailer block, which has a plurality of teeth 10^a adapted to fit over the teeth of the sprocket wheel 15, as best shown in Fig. 3, the trailer block then resting upon the sprocket in a substantially balanced position.

Chain 11 is preferably formed of links having a pair of side members 11^a pivoted on cross pins 11^b of a length greater than the width of the guide plate 13 and the sprocket wheel 15 over which the chain passes. Between the side members 11^a are arranged a plurality of spacer members 11^c pivoted on alternate pins 11^b from the side members (see Fig. 10). The spacer members 11^c are of a combined thickness equal to or greater than the width of the sprocket wheel 15 and are arranged so as to cover substantially all of the cross pins 11^b except a portion equal to the thickness of the guide plate 13. With this construction one of the side links 11^a contacts one side of the guide plate 13 while the adjacent spacer member 11^c contacts the opposite side of the guide plate 13, giving a substantial support for the chain in its movements and providing an uncovered portion of each cross pin 11^b within the slot. The spacer members 11^c space the other side links 11^a from the guide plate 13 a sufficient distance to permit the entrance of the

sprocket teeth into the spaces 11^a between the ends of the spacer members 11^c at the same time that the chain is guided in its movement by the guide plate 13.

5 The sprocket wheel 15 is fixed upon a stub shaft 16 journalled in the channelled guide plate 13 and a base plate 17 secured to the car body adjacent the upper extremity of the regulating mechanism. The stub shaft 10 16 also carries a gear wheel 18 adapted to mesh with a pinion 19 loosely mounted on the stub shaft 20 to which the handle 21 is fixed, means being provided between the handle and the pinion 19 for automatically 15 locking the regulating mechanism in any adjusted position.

The locking mechanism serves to maintain the window at any desired height, and comprises a key-receiving plate 22 fixed onto 20 the hub of the pinion 19 and provided with a pair of diametrically opposed notches 23 in its periphery adapted to receive a pair of floating discs or keys 24 which serve both as locking members and as keys for connecting the pinion and plate 22 with the mechanism carried by the handle 21 presently to be described.

The discs 24 fit into notches 25 in the fixed plate 26 (see Fig. 6) when extended beyond 30 the periphery of the plate 22, in which position they prevent the rotation of the plate 22 and its attached pinion 19. A pick-up plate 27 is fixed upon the shaft 20 carrying the handle 21 and is formed with diametrically opposed cam-slots 29 of substantially the shape shown in Fig. 6, the central portion of the slot having a projecting cam 29^a adapted to force the floating discs 24 into the slots 25 of the fixed plate 26 whenever the 35 handle 21 is released by the operator. This action of the cam 29^a is secured by arranging a pair of springs 30 in curved slots between the cam-slots on opposite sides of the shaft, the ends of each spring pressing against the 40 end walls of the slots in both the key-receiving plate 22 and the pickup plate 27. The springs 30 normally position the plates 22 and 27 so that the cam portion 29^a is in alignment with the notches 23 of the 45 key-receiving plate 22, forcing the discs 24 in locking engagement with the notches 25 of the fixed plate 26. When the handle 21 is turned, however, in either direction the pick-up plate 27 is rotated against the tension 50 of the springs 30, moving the cams 29^a out of engagement with the discs 24 and bringing the curved end portions of the slots 29 into contact with the discs 24 withdrawing them from the locking notches 25 55 and moving them together with key-receiving plate 22 to rotate the pinion 19.

The rotation of the pinion 19 drives the gear wheel 18 and sprocket wheel 15 to move the chain 11 in its guide 12 to elevate or 60 lower the window to the desired height.

The handle 21 is thereupon released and the springs 30 return the cams 29^a into alignment with the notches 23 in the key receiving plate 22, again forcing the floating keys 24 into locking engagement with the notches 25 then nearest the keys. By providing the notches 25 in substantially continuous relation around the opening in the fixed plate 26 the discs 24 will seat into adjacent notches at practically any point. 75

The shaft 20 is preferably rounded on one extremity to provide a bearing for the key-receiving plate 22 and pinion 19 while adjacent its opposite extremity it is squared to form a driving connection with the hub 80 of the handle 21 and the pick-up plate 27. The handle 21 is retained against longitudinal movement on the shaft 20 by means of a key 31 loosely set in aligned slots 32 and 33 in the shaft 20 and handle hub respectively (note Fig. 2). A sleeve 34 normally covers the key 31 to prevent its accidental dislocation, a coil spring 35 being arranged between the rear extremity of the sleeve 34 and the central portion of an escutcheon plate 36 arranged to cover the upholstery adjacent the hub of the handle. The spring 35 forces the sleeve 34 forwardly and also presses the escutcheon plate 36 rearwardly into firm engagement with the upholstery. 90 When it is desired to disconnect the handle 21 from the shaft 20, the sleeve 34 is pressed rearwardly against the tension of the spring 35 until the key 31 is uncovered, whereupon the key can be lifted from its slot and the 100 handle hub slid from the shaft.

The above described mechanism operates to raise and lower the window to any desired position and maintain it at such position. No counterbalance for the weight of the window is necessary since the mechanism is positively driven in both directions. However when it is desired to lessen the work performed by the operator a counterbalanced mechanism may be provided as illustrated in Figs. 8 and 9, wherein is shown spring 37 coiled within a housing 38 and secured to a stub-shaft 39 which also carries a gear 40 arranged to mesh with the gear wheel 18 of the regulating mechanism. 110 The direction of rotation of the gear 40 by reason of the tension of the spring 37 is such that the spring tends to elevate the window to the same extent that the weight of the window tends to lower it by force of gravity. If desired the tension of the spring 37 can be increased to perform part of the work of the operator as soon as the floating keys 24 are released from the locking notches 25. As shown in Fig. 8 the counterbalancing mechanism is mounted upon the channelled guide plate 13 below the sprocket wheel 18 and in such position will not interfere with the operation of the regulating mechanism, regardless of whether the pinion 19 is ar- 120 125 130

ranged at the left or right hand side of the sprocket wheel.

The pinion and associated mechanism is shown in Fig. 4 as located at the right hand side of the gear wheel 18, and in such position is adapted to raise and lower the windows on one side of the car. To raise and lower the windows on the opposite side of the car, identically the same mechanism is employed but the pinion 19 and the mechanism associated therewith on the handle shaft 20 is mounted on the left hand side of the gear wheel 18. In Fig. 4 is shown an opening 41 in the guide plate 13 in which the shaft 20 is adapted to be journaled when in position on the left hand side of the gear 18.

While it will be apparent that the illustrated embodiments of my invention herein disclosed are well calculated to adequately fulfill the objects and advantages primarily stated, it is to be understood that the invention is susceptible to variation, modification and change within the spirit and scope 25 of the subjoined claims.

Having described my invention, I claim:—

1. In a device of the character described, a window and means for raising or lowering the window including a channeled plate having an inverted U-shaped guide slot therein, a chain guided in said slot, and a trailer block carried by the chain and engaging the window, the trailer-block resting upon the lower wall of one of the legs of the slot when the window is in its lowermost position and the opposite end of the chain engaging the lower wall of the other leg of the slot when the window is in its topmost position.

2. In a device of the character described, a window, and means for raising or lowering the window including a channeled plate having an inverted U-shaped guide slot therein, a sprocket wheel mounted concentrically of the curved portion of the slot and meshing with the chain, and a trailer-block carried by the chain and engaging the window, the trailer-block resting upon the lower wall of one of the legs of the slot when the window is in its lowermost position and resting upon the sprocket wheel when the window is in its topmost position.

3. In a device of the character described, a window, and means for raising or lowering the window including a channeled plate having an inverted U-shaped guide slot therein, a chain guided in said slot, a sprocket wheel mounted concentrically of the curved portion of the slot and meshing with the chain, a trailer-block carried by the chain and engaging the window, a gear wheel fixed to rotate with the sprocket wheel, a pinion meshing with the gear, and a handle for turning the pinion.

4. In a device of the character described,

a window, and means for raising or lowering the window including a channeled plate having an inverted U-shaped guide slot therein, a chain guided in said slot, a sprocket wheel mounted concentrically of the curved portion of the slot and meshing with the chain, a trailer-block carried by the chain and engaging the window, a gear wheel fixed to rotate with the sprocket wheel, a pinion meshing with the gear, a handle, and a clutch intermediate the handle and pinion.

5. In a sash regulating device wherein rotation of an arbor is adapted for raising and lowering a sash or like member: a wheel adapted to be driven by said arbor, a casing enclosing said wheel and provided with longitudinally parallel guideways and a flexible member articulated with the sash and trained over said wheel, said flexible member having its ends guided in the casing guideways, said wheel and flexible member having an engagement by which said flexible member is supported by said wheel independent of the driving relation between said wheel and flexible member.

6. In a sash regulating mechanism, wherein in rotation of an arbor is adapted for raising a sash or the like, a casing, a wheel adapted to be driven by said arbor, and a flexible member co-operating with the wheel to provide movement to and support the sash, said member having one end operatively connected with the sash and its opposite end free, movement of the member being provided by engagement of wheel and member intermediate the member ends, said casing having guideways for the opposite ends of the member and co-operating with the member and wheel in providing movement of the member in a fixed travel path throughout the length of the member.

7. In a sash regulating mechanism, wherein in rotation of an arbor is adapted for raising a sash or the like, a casing, a wheel adapted to be driven by said arbor, and a flexible member co-operating with the wheel to provide movement to and support the sash, said member having one end operatively connected with the sash and its opposite end free, movement of the member being provided by engagement of wheel and member intermediate the member ends, said casing having guideways for the opposite ends of the member and co-operating with the member and wheel in providing movement of the member in a fixed travel path throughout the length of the member, characterized in that the guideways extend symmetrically relative to the travel path of the member about the wheel and in directions substantially parallel with each other.

8. In a sash regulating mechanism, wherein in rotation of an arbor is adapted for raising a sash or the like, a casing, a wheel adapted to be driven by said arbor, and a

flexible member co-operating with the wheel to provide movement to and support the sash, said member having one end operatively connected with the sash and its opposite end free, movement of the member being provided by engagement of wheel and member intermediate the member ends, whereby the member length is divided into a tensioned section and a slack section with the length of the sections varying in correspondence with the movement of the sash by the wheel movements, said casing having a guideway for the slack section of the mem-

ber with the guideway extending tangential to the path of travel of the member in rounding the wheel, movement of the slack section within the guideway being provided by movement of the wheel in pushing or pulling such section depending upon the direction of movement of the wheel, whereby the slack section will travel within a predetermined travel path. 15
20

In witness whereof I hereunto set my hand.

JOHN HAYWARD PARSONS.
